UNITED STATES PATENT OFFICE.

OSTRANGER J. PARKS, OF RIVER FOREST, ILLINOIS, ASSIGNOR TO GENERAL AMERICAN TANK CAR CORPORATION, OF CHICAGO, ILLINOIS, A CORPORATION OF WEST VIRGINIA.

RECEPTACLE.

1,384,915.

Specification of Letters Patent. Patented July 19, 1921.

Application filed December 15, 1919. Serial No. 345,097.

To all whom it may concern:

Be it known that I, OSTRANGER J. PARKS, a citizen of the United States, residing at River Forest, in the county of Cook and 5 State of Illinois, have invented a new and useful Improvement in Receptacles, of which the following is a specification.

My invention relates more particularly to receptacles in which substances of such character that a pressure is generated therein, such as for example gasoline, are stored, 10 my invention having particular reference to tank cars for explosive fluids; and my object, generally stated, is to provide a 15 novel, simple and economical construction of removable cover for the manhole of the receptacle to the end that a positive closure will be effected and injury to the workman in removing the cover from the receptacle 20 will be prevented.

Referring to the accompanying drawings:—Figure 1 is a plan view of a manhole, or dome, ring which in practice would be securely fastened to the top of the receptacle 25 to surround the opening to be controlled by the cover, the cover for the manhole being shown in position thereon. Fig. 2 is a similar view of the ring of Fig. 1 with the cover removed, and the nuts on the studs of the 30 dome ring also removed. Fig. 3 is an enlarged section taken at the line 3 on Fig. 1 and viewed in the direction of the arrow, this view showing the structure of Fig. 1 as assembled with the tank of a tank car, 35 the tank being shown broken away. Fig. 4 is a broken, enlarged, sectional view taken at the line 4 on Fig. 1 and viewed in the direction of the arrow, showing the structure assembled with a tank, the latter being 40 broken away; and Fig. 5, a similar view taken at the line 5 on Fig. 1 and viewed in the direction of the arrow, also showing the structure of this figure assembled with the tank.

45 In the arrangement shown, the upper surface of a tank car is represented at 6, this surface being formed with the usual manhole 7, and which is equipped with a structure embodying my invention. The upper portion 6 of the tank is shown to represent the construction as usually provided, namely the inner wall portion 8 and the outer wall 50 portion 9 spaced therefrom, there being secured to the upper surface of the portion 8 a flanged manhole, or dome, ring 10 which

surrounds the manhole 7, the ring 10 being secured to the wall portion 8 as by means of rivets indicated at 11. The ring 10, in accordance with common practice, is provided with the filling opening 12 and the 60 vent opening 13, the opening 12 having screwed thereto from its lower end a pipe 14 which reaches preferably to a point close to the bottom of the tank and through which the fluid is introduced into the tank. 65 The openings 12 and 13 are provided with removable plugs or caps 15 and 16, respectively, for closing these openings to the atmosphere. The ring 10 is provided with an annular series of stud-bolts 17 which extend upwardly therefrom and are preferably spaced equidistantly apart with the series thereof concentric with the manhole 7 as shown, the upper ends of these studs 70 being threaded. The inner marginal edge 75 of the ring 10 which extends over the opening 7 contains, in its upper surface, an annular channel 18 for receiving a gasket 19^a, as for example of lead, for aiding in the forming of a tight joint between the cover 80 and the ring 10.

The cover for the manhole 7 is represented at 19, the body or plate portion 20 of the cover being provided with a depending annular flange 21 at which the cover extends 85 into the opening in the ring 10 and with a depending annular flange 21 adapted to engage the gasket 19^a when the cover is in position. The body 20 of the cover is provided about its periphery with a series 90 of recesses 22 which extend in a circumferential direction, these recesses opening in the same direction and being of a number equal to the number of studs 17 and similarly spaced apart, the periphery of the body 95 portion 20 at points between adjacent ones of the recesses 22, being notched as indicated at 23 for a purpose hereinafter explained. The cover 19, when in sealing position, occupies the position shown in Fig. 100 1 wherein it will be noted the studs 17 extend into the recesses 22 of the cover, in which position the cover is held down securely by nuts 24 screwed upon the upper ends of the studs 17 and engaging the upper surfaces of the recessed portions 22 of the cover to provide added strength for the recessed portions 22 and an easier release from the nuts 24 the extended portions in which the recesses 22 are formed are 110

thickened and their upper surfaces are out departing from the spirit of my invention. raised above the plane of the top of the cover 19.

The cover is also shown as formed with 5 upwardly extending lugs 25 apertured as indicated at 26 and which serve, in conjunction with an apertured lug 27 on the plug 15 to receive a sealing wire 28 for the usual purpose. The cover 19 is also provided with an eye 29 secured thereto in depending position for connection with a chain 30 which is connected at its opposite end with an eye 31 secured to, and depending from, the ring 10, this construction serving 10 as a means for restraining the cover from dropping to the ground when it is removed from the manhole and freed from the grasp of the operator.

It will be understood from the foregoing 20 that the workman, to remove the cover 19, may first loosen the nuts 24 sufficiently to permit turning of the cover to a position in which the latter is out of interlocked position with these nuts, such position in 25 the particular construction illustrated being that in which the recessed portions 23 of the cover register with the nuts 24, the operator then lifting the cover free of the tank to permit access of the latter through the 30 manhole.

The feature of providing the nuts which have overlapping relation to the cover in one position of the latter, and the adaptability of the cover to its removal from the tank, without removing the nuts, is of great 35 advantage inasmuch as pressure which may have accumulated in the tank and to which the cover is subjected, is permitted to escape 40 from the manhole 7 around the cover 20 upon loosening the nuts 24, but the cover is prevented from being blown from the tank by its interlocking relation with the nuts, thereby avoiding injury to the workman, 45 the cover being readily removable, following the loosening of the nuts 24 by merely rotating it to the releasing position referred to.

While I have illustrated and described a 50 particular construction embodying my invention, I do not wish to be understood as intending to limit it thereto as the same may be variously modified and altered with-

What I claim as new and desire to secure by Letters Patent is:

1. The combination with a receptacle containing an opening, of closure means therefor comprising a cover and shouldered members on the tank, the shoulder portions of which are vertically adjustable toward and away from the tank, said cover being adapted to be rotated at said opening and provided at intervals, at its marginal portion, with radially-extending thickened portions which are spaced from the body of the cover and extend beyond the edge thereof with their upper surfaces raised above the plane of the cover and which with the latter form circumferentially-extending recesses which extend in the same direction, and each presenting, by reason of said radially-extending portions and the adjacent portions of said body portion, a pair of surfaces spaced apart and adapted, in one position of said cover, to interlock with said shoulder portions and limit outward movement of said cover, but be out of interlocked relation with said shoulder portions when rotated to another position of said cover, adapting the cover to be bodily removed from the tank.

2. The combination with a receptacle containing an opening, of closure means therefor comprising a ring secured to the top of the receptacle and surrounding the opening, said ring being equipped with an annular series of studs extending upwardly therefrom and having screw threaded upper portions, nuts screwing on said studs and a cover provided with a series of circumferentially-disposed recesses, the edges of the cover surrounding said recesses being thickened and extending beyond the nuts and overlapping said ring, said recesses being adapted in one position of said cover to partially surround and interlock the said nuts whereby to limit outward movement of said cover, and to be turned out of interlocking relation with said nuts when said cover is rotated to another position, whereby the cover is adapted to be bodily removed from the receptacle.

OSTRANDER J. PARKS.
